[57] CLAIM

The ornamental designs for a vermicomposting container, as shown and described.

DESCRIPTION

FIG. 1 is an exploded top perspective view of a vermicomposting container showing my new design;

FIG. 2 is a front elevational view thereof without its lid. The lid of the container is omitted for clarity of illustration;

FIG. 3 is a rear elevational view of FIG. 2;

FIG. 4 is a top plan view of FIG. 2;

FIG. 5 is a bottom plan view of FIG. 2;

FIG. 6 is a left side elevational view of FIG. 2, the right side elevational view being a mirror image of that shown;

FIG. 7 is a top plan view of a lid of the container;

FIG. 8 is a bottom plan view of FIG. 7;

FIG. 9 is a front elevational view of FIG. 7, the rear elevational view being a mirror image of that shown;

FIG. 10 is a left side elevational view of FIG. 7, the right side elevational view being a mirror image of that shown;

FIG. 11 is an exploded top perspective view of second embodiment of the vermicomposting container;

FIG. 12 is a front elevational view of FIG. 11 without its lid;

FIG. 13 is a rear elevational view of FIG. 12;

FIG. 14 is a top plan view of FIG. 12;

FIG. 15 is a bottom plan view of FIG. 12;

FIG. 16 is a left side elevational view of FIG. 12, the right side elevational view being a mirror image of that shown;

FIG. 17 is an explode top perspective view of a third embodiment of the vermicomposting container;

FIG. 18 is a front elevational view FIG. 17 without its lid;

FIG. 19 is a rear elevational view of FIG. 18;

FIG. 20 is a top plan view of FIG. 18;

FIG. 21 is a bottom plan view of FIG. 18; and,

FIG. 22 is a left side elevational view of FIG. 18, the right side elevational view being a mirror image of that shown.

The bottom of the lid of second and third embodiment of the vermicomposting container is flat and unornamental.
